UNITED STATES PATENT OFFICE.

JACOB LEVY, OF NEW YORK, N. Y., ASSIGNOR TO THE LEE IMPROVEMENT COMPANY, OF NEW YORK, N. Y., A CORPORATION OF NEW YORK.

STRAINER.

No. 926,704.

Specification of Letters Patent.

Patented June 29, 1909.

Application filed July 22, 1908. Serial No. 444,708.

To all whom it may concern:

Be it known that I, JACOB LEVY, a citizen of the United States, and a resident of the city of New York, in the county of New York 5 and State of New York, United States of America, have invented certain new and useful Improvements in Strainers, of which the following is a specification.

My invention relates to strainers such as 10 are used in conjunction with roof leaders or vent pipes, and its object is to improve upon devices of this class and to provide a wire basket strainer of simple construction which may be readily affixed to the end of a pipe 15 by a novel arrangement which I have invented.

To these ends my invention resides in the construction and arrangement of parts described in the following specification, the 20 novel features whereof are set forth in appended claims.

Referring to the drawings, Figure 1 is a sectional side elevation of the upper end of a pipe with my improved strainer attached to thereto. Fig. 2 is a sectional plan view of 25 some of the parts shown in Fig. 1, the section being taken on the line 2—2 of the latter figure. Fig. 3 is a sectional side elevation of the pipe to which the strainer is to be 30 affixed, and the lower end of the strainer showing my novel fastening arrangement and the manner in which it is used.

Like characters of reference designate 35 corresponding parts in all of the figures. 10 designates the upper end of a roof leader or other structure in conjunction with which it is desired to use a strainer.

11 is the strainer which may be made in many forms and by different constructions. 40 For example, it may be made in the shape and in the manner shown in Fig. 1, in which 12 designates a circular wire hoop around which the ends of a plurality of wires 13 are bent. These wires are then carried down in 45 such a way as to form a basket with its upper portion cone-shaped. They are then bent over a second wire hoop 14 to which they are fastened by means of a binding wire 15. 16 is a third circular wire hoop through 50 which the wires 13 pass. These may be bent to engage with the hoop 16 in the manner shown, or, if desired, may be fastened thereto in some such manner as they are fastened to the hoop 14. From the hoop 16 the wires

extend downward in practically cylindrical 55 form and are each permanently affixed to a split band 17.

20 and 21 designate a pair of levers which are connected by means of brackets 22 and 23 to the band 17 at diametrically opposite 60 points. 24 is a similar lever connected to the band 17 at a point midway between the brackets 22 and 23 by a similar bracket 25. 26 and 27 are other levers connected by brackets with the two ends of the split band 65 17. The levers 20 and 21 are slidably connected together near their inner ends by means of a rivet 28. 29 designates a similar rivet connecting together the levers 24, 26 and 27. 70

In Figs. 1 and 3 it may be seen that the levers 26 and 27 are provided with slots through which the pin or rivet 29 may slide. 30 designates a washer which is placed between the levers 24 and 26. This washer is 75 for a purpose which will fully appear hereinafter. It may be seen that the brackets which fasten these levers to the inner surface of the split band may be carried down under the lower edges of the levers into such a position as to limit the downward movement of the levers. Or, if desired, one of each 80 pair of levers may be constructed as shown at 27^a to accomplish this purpose.

Now, when it is desired to affix the strainer 85 above described to the end of a pipe or other object, the cylindrical-shaped portion of the strainer is thrust within the pipe with the levers bent upward into the position in which they are shown in Fig. 3. The levers 20 and 21 are then pushed down until they are in 90 horizontal alinement, which will, of course, produce a toggle-joint leverage which will press the split band 17 outward against the inner surface of the pipe. The levers 24, 26 95 and 27 are then pressed downward until they are all in horizontal alinement, which movement will again expand the split band and cause it to be pressed outward against the inner surface of the pipe. 100

The parts above described, with the exception of the washer 30, are preferably constructed of some non-rustable material such, for example, as galvanized iron. The washer 30, however, is of iron not galvanized, so that 105 as soon as it is exposed to moisture it will become oxidized and will rust in place, thus locking the levers together. As the levers 20

and 21 are below levers 24, 26 and 27, these too will be locked in position by the rusting of the washer 30.

It is evident that if desired, washers similar to that designated by the numeral 30, may be placed between the levers 20 and 21, and also similar rustable levers may be placed between each of the levers and the bracket which connects it with the split band 17. 10 This arrangement provides a strainer which may be permanently affixed in a moment and without the use of tools to the end of a pipe or other similar desired opening. It effectively does away with the necessity of cutting or tapping the pipe and with the use of solder. It is cheap to manufacture and simple to use.

The fastening device which I have shown herein may, of course, be used in conjunction 20 with other forms of strainers and with other devices than that which I have selected to illustrate its use.

What I claim is—

1. A strainer comprising a split annular band adapted to fit within a circular body to which the strainer is to be attached, and means for expanding said band within the body and for forming a rust-joint to permanently hold the band within said body.

30 2. A strainer comprising a split annular band adapted to fit within a circular body to which the strainer is to be attached, a lever arranged to expand and hold said band within the body, and means for forming a rust-joint for locking said lever in place.

35 3. A strainer comprising a split annular band adapted to fit within a circular body to which the strainer is to be attached, a pair of

toggle levers connected with said band within the body, and means for forming a rust-joint 40 to hold said levers in place.

4. A strainer comprising a split annular band adapted to fit within a circular body to which the strainer is to be attached, a pair of toggle levers connected with said band and 45 to each other and arranged to expand and hold the band within the body, and means for forming rust-joints at the connections of said levers for holding said levers in place.

5. In combination with a pipe, a strainer 50 comprising a split band adapted to fit within said pipe, a plurality of levers pivotally connected with said band and with one another, said levers being arranged to expand and hold the band within the pipe, and a rustable 55 washer at one of said lever connections arranged to form a rust-joint at said connection and hold the levers in place.

6. In combination with a circular pipe, a wire strainer comprising a split annular band 60 adapted to fit within said pipe, a plurality of toggle levers pivotally connected to the inside of said band and with one another, said toggle levers being arranged to expand and hold the band within the pipe, and rustable 65 washers at said lever connections arranged to form rust-joints at said connections to hold them in place.

In testimony whereof I have signed my name to this specification in the presence of 70 two subscribing witnesses.

JACOB LEVY.
